BOX TREATING APPARATUS

Charles B. Cook, Los Angeles, Calif.

Application June 20, 1938, Serial No. 214,773

4 Claims. (Cl. 21—80)

This invention relates to improvements in box treating apparatus.

The general object of my invention is to provide an improved apparatus which is particularly adapted for use in treating citrus field boxes in such a manner that mealy bugs or any other detrimental or injurious pests will be destroyed, and wherein the box will be preserved.

A further object of my invention is to provide an improved box treating apparatus which is compact and wherein novel circumferentially arranged box moving means is provided.

Another object of the invention is to provide a box treating apparatus wherein a container is provided with a novel sprocket chain arranged spirally and in a fashion so that boxes may be moved thereon and wherein novel means is provided for treating the boxes while they are being moved.

20. A further object of the invention is to provide a box treating apparatus including a cylindrical container having a reduced central cylindrical column therein and a sprocket chain arranged spirally around the central column to 25 convey boxes from adjacent the top thereof to adjacent the bottom thereof.

An additional object of my invention is to provide a novel sprocket chain.

Other objects and the advantages of this invention will be apparent from the following description taken in connection with the accompanying drawings, wherein:

Fig. 1 is a side elevation of my improved box treating apparatus;

35. Fig. 2 is a section taken on line 2—2 of Fig. 1 with portions broken away;

Fig. 3 is a view of the discharge side of the device with portions broken away;

Fig. 4 is a section taken on line 4—4 of Fig. 2;

40. Fig. 5 is a section taken on line 5—5 of Fig. 2;

Fig. 6 is an enlarged fragmentary section taken on line 6—6 of Fig. 4;

45. Fig. 7 is an enlarged fragmentary elevation taken on line 7—7 of Fig. 4 with portions broken away;

Fig. 8 is an enlarged sectional view of the insecticide pump;

50. Fig. 9 is an enlarged fragmentary top plan view, partly in section, showing the conveyor chain;

Fig. 10 is a section taken on line 10—10 of Fig. 9;

55. Fig. 11 is an enlarged fragmentary section taken on line 11—11 of Fig. 4;

Fig. 12 is an enlarged fragmentary sectional detail of the entrance closure device;

Fig. 13 is an enlarged fragmentary section taken on line 13—13 of Fig. 1;

Fig. 14 is an enlarged fragmentary section taken on line 14—14 of Fig. 5;

Fig. 15 is an enlarged fragmentary section taken on line 15—15 of Fig. 13;

Fig. 16 is an enlarged detail view, partly in section, showing the gas and water flow control device;

Fig. 17 is a view similar to Fig. 1 showing a modified form of my invention;

Fig. 18 is a section taken on line 18—18 of Fig. 17; and

Fig. 19 is a fragmentary section showing the location of the spray nozzle in the modification.

Referring to the drawings by reference characters I have illustrated my invention as embodied in a box treating apparatus which is indicated generally at 10. As shown the device 10 includes a circular container or housing 12 which is mounted on a base frame 13.

The housing 12 includes side walls 14, a bottom wall 15 and a top wall 16. Centrally positioned in the housing 12 and extending from the bottom to the top thereof I provide a hollow circular column member 17 which is of less diameter than the housing.

Below the housing 12 I provide an air blower member 18 which includes an inlet conduit 19 and an outlet conduit 20. The blower is adapted to be driven by an electric motor 21. As shown the blower inlet conduit 19 extends upwardly into the housing through a suitable aperture in the bottom wall 15. The upper end of the blower inlet conduit 19 is positioned in the space between the side walls of the housing 12 and the column 17 and extends a predetermined distance above the bottom wall 15. The blower outlet conduit 20 extends upward through a suitable aperture in the bottom wall 15 and opens into the interior of the column 17.

In the present construction I have shown my apparatus as adapted to receive boxes at entrance A (Figs. 1 and 4) which is located adjacent the top of and at one side of the center of the housing 12.

The boxes are adapted to be discharged from the apparatus at exit B which is located adjacent the bottom of the housing and is positioned at the rear of the housing.

For conveying boxes such as indicated at 22 from the entrance A to the exit B I provide an endless sprocket chain which is indicated gen-

15

30

35

40

45

55

erally at 23 and shown in detail in Figs. 9 and 10. The chain 23 is helically arranged around the column 17 intermediate the column and the side walls of the housing.

- 5 Adjacent the entrance A the chain 23 is supported on a drive sprocket 24 which is mounted on a shaft 25 which is journaled in suitable bearings 26 and extends through the side of the housing 12 where it has a sprocket 27 thereon.
- 10 The sprocket 27 is driven by a sprocket chain 28 from a sprocket 29 on the armature shaft of an electric motor 30 which is shown as mounted on a suitable bracket 31 extending outwardly from the top of the housing.
- 15 Adjacent the exit B the chain 23 is supported on an idler sprocket 32 and whence it passes through a suitable aperture in the bottom wall 15 and curves towards the entrance side of the device to a location directly below the drive sprocket 27 where it extends upwardly over an idler sprocket 33.

Between the drive sprocket 24 and the idler sprocket 32 the chain is supported and guided by an angle iron chain guide member 34 which is helically arranged around the column 17 intermediate the side walls of the housing and the column. The angle iron member 34 is positioned with one flange thereon vertical and with the vertical flange towards the column 17. The angle iron member 34 is supported throughout its length by a plurality of spaced transverse members 35 which are suitably secured to the side walls of the housing and the central column as by welding them thereto.

- 30 As shown in Figs. 9 and 10 the conveyor chain 23 comprises a plurality of link members 36 each of which includes a section 37 and a section 38. The sections 37 and 38 have a flat top and the section 37 includes a recessed portion 39 to receive a horizontal roller 40 which lies below the top of the section 38. The sections 37 and 38 and the roller 40 are connected by a suitable pivot member 41. The diameter of the rollers 40 is greater than the width of the chain links and the rollers are adapted to engage the vertical flange of the chain guide 34 (see Figs. 9 and 10). The link section 37 includes a pair of spaced downwardly extending flange portions 42 between which a roller member 43 is positioned. The link section 38 includes a pair of spaced downwardly extending flange portions 44 between which the flange portions 42 of the section 37 are positioned. The flange portions 42 of the section 37, the flange portions 44 of the section 38 and the roller 43 are connected by a suitable pivot member 45. The rollers 43 extend below the downwardly extending flanges of the chain links and engage the horizontal flange of the chain guide 34 to support the conveyor chain. When the rollers 43 are in engagement with the outwardly extending flange of the chain guide 34 the tops of the chain links extend above the vertical flange of the chain guide. Thus when a box is positioned on the conveyor chain it will not contact the chain guide 34.

Extending inwardly from the chain guide 34 I provide a plurality of rollers 47 which are evenly spaced throughout the length of the chain guide. As shown in Fig. 11 each of the rollers 47 is rotatably mounted on a rod 48 which is secured to the vertical flange of the chain guide 34 as by welding it thereto.

Intermediate the chain guide 34 and the side walls of the housing 12 I provide a pipe member 49 which extends from the entrance A to the

exit B and is helically arranged to match the curvature of the chain guide 34. Like the chain guide the pipe 49 is supported by brackets 50 on the transverse members 35.

The tops of the rollers 47 and the top of the pipe 49 are slightly below the tops of the links of the conveyor chain 23 so that a box on the conveyor chain does not normally contact either the rollers 47 or the pipe 49. Should a box during the course of its travel become unbalanced on the conveyor chain and tilt to one side or the other either the rollers 47 or the pipe 49 will limit the tilting.

In order to provide a closure for the housing entrance and exit I employ a closure member 51 which is shown in detail in Fig. 12. This closure member comprises a shaft 52 on which a plurality of flat metal strips 53 are mounted. These strips hang free and have their upper ends looped around the shaft 52. An angle member 54 serves to limit the movement of the strips 53 in one direction.

For heating the air which is circulated in the housing 12 I provide a gas burner member 55 which is positioned in a container 56 in the bottom wall 15 (see Figs. 5 and 14). As shown the upper edges of the container 56 extend above the bottom 15 a predetermined distance so that water which is placed in the bottom of the housing will not flow into the container.

Gas is furnished to the burner 55 by means of a pipe 57 which communicates with one side of a control valve 58. The other side of the control valve has a gas supply pipe 59 communicating therewith which has a shut off valve 60 interposed therein.

As shown in Fig. 14 the bottom 15 has a vertical drain pipe 61 therein which is externally threaded to receive an internally threaded closure cap 62. The closure cap 62 has a vertical overflow pipe 63 therein the upper end of which extends above the bottom 15 to a position below the upper edges of the burner container 56.

Adjacent the inside of the exit B I provide a vertical bulkhead 64 which extends from the housing side wall to the column 17 and from the bottom 15 upward to adjacent the transverse support members 35 thereabove.

Above the burner 55 I provide a water tank 65 which extends from the bulkhead 64 part way around the housing and from the central column to the side walls of the housing 12. A portion of the water tank 65 is covered by a solid member 66 and the remainder is covered by a screen member 67 to prevent refuse from falling into the tank. The bottom wall of the water tank 65 has a vertical drain pipe 68 therein which is externally threaded to receive an internally threaded closure cap 69. The closure cap 69 has a vertical overflow pipe 70 therein the upper end of which extends upward into the water tank 65 a predetermined distance below the top thereof.

Positioned in the central column 17 below the water tank 65 and above the upper end of the blower inlet conduit 19 I provide a horizontal conduit 71. One end of the conduit 71 is positioned adjacent the blower inlet conduit 19 and the opposite end is positioned adjacent the opposite end of the burner so that heated air may be drawn from the space at that end of the burner into the blower inlet conduit.

Adjacent the water tank 65 on the outside of the housing 12 I provide a tank 72 which has a pipe 73 extending therefrom into the housing and into the water tank 65. Another pipe 74 ex-

tends upward into the tank 72 and terminates in a float controlled valve 75 (Fig. 3). The opposite end of the pipe 74 communicates with a pipe 76 which extends upward in the central column 17 to adjacent the top thereof and then descends in coiled formation as at 77 and terminates in one side of a shut off valve 78. The opposite side of the valve 78 has a water supply pipe 79 communicating therewith which in turn communicates with a suitable source of water supply not shown.

Also communicating with the pipe 76 I provide a pipe 80 which has a shut off valve 81 interposed therein and communicates with a control valve 82 which is located adjacent the gas control valve 58. From the valve 82 a pipe 83 extends into the housing 12 to provide water in the bottom of the housing.

As shown in Fig. 16 the gas control valve 58 is of the type which includes a vertically movable operating stem 84 which when moved upward restricts passage through the valve. The water control valve 82 is of the type which includes a vertically movable operating stem 85 which when moved downward restricts passage through the valve.

The gas control valve stem 84 is slackly connected adjacent one end of a horizontal beam member 86 as at 87. The water control valve stem 85 is slackly connected adjacent the opposite end of the beam 86 as at 88. Intermediate the valves the beam member 86 has a V notch 89 in the upper face thereof. Positioned in the V notch 89 I provide a triangular fulcrum bar 90 which is supported in a bracket 91 mounted on the bottom plate 15. Above the bracket 91 adjacent the top of the housing I provide a bracket 92 which extends outwardly from the housing and has a depending rod 93 rigidly secured thereto. The rod 93 is made of metal having a low coefficient of expansion and the lower end thereof includes a threaded portion 94 on which an inverted U-shaped stirrup 95 is secured by nuts 96.

Intermediate the valve 58 and the notch 89 the beam 86 has an inverted V notch 97 in the lower face thereof in which a triangular pivot bar 98 carried by the stirrup 95 is positioned. Above the stirrup 95 the rod 93 has an arm member 99 projecting therefrom towards the valve 82. The upper end of a coiled spring 100 is connected to the arm 99 and the lower end of the spring is connected to the beam 86 as at 101.

When the device is operating and the heat within the housing is sufficient to expand the metal side walls of the housing the rod 93 is moved upwardly therewith thus swinging the end of the beam 86 towards the valve 58 upward and thereby operating the gas control valve toward a closed position. At the same time the end of the beam 86 towards the valve 82 swings downward thereby operating the water control valve 82 towards a closed position.

As shown in Fig. 6 at one station on the apparatus I provide a conduit 102 which extends outwardly from the central column 17 and opens thereto, the opposite end of the conduit being closed. Intermediate the length thereof the conduit 102 has an opening 103 in the lower face thereof. Positioned in the conduit 102 I provide a pipe 104 which includes a downwardly directed end portion which is positioned in the conduit opening 103 and has a spray nozzle 105 thereon below the conduit.

As clearly shown in Fig. 7 the pipe 104 extends downwardly to a pump member 106 ad-

jacent which it has a check valve 107 interposed therein. The pump 106 is positioned in a container 108 which has a partition 109 thereacross to form a tank portion 110.

The pump 106 may be of any standard type 5 which includes a casing 112 (see Fig. 8) having a diaphragm 113 therein which is connected to a rod 114. The pump includes an inlet pipe 115 opening thereto with the opposite end positioned in the tank portion 110. Adjacent the 10 pump the inlet pipe 115 has a check valve 116 interposed therein.

Adjacent the top reach of the conveyor chain 23 I provide an arm member 117 which is mounted on a shaft 118 and includes an upwardly bowed 15 portion 119 which is positioned between the conveyor chain 23 and the pipe 49 and projects upwardly into the path of travel of the boxes 22 in the apparatus.

The shaft 118 is supported in a suitable bearing 120 (see Fig. 4) and extends out of the housing 12 where it has a lever arm 121 thereon extending oppositely to the arm 117. The lever arm 121 is connected by a link 122 with one end of an arm 123 which is pivoted intermediate its 25 length as at 124 to a bracket 125 in the container 108. The opposite end of the arm 123 is slackly connected to the pump rod 114 as at 126. In operation the tank portion 110 is filled with a liquid insecticide as shown in Fig. 7. 30

From the foregoing description it will be apparent that when the arm 117 is moved downwardly by a box the diaphragm 113 of the pump will be moved downwardly to cause a change of insecticide in the tank 110 to be drawn into 35 the casing 112. When the arm 117 returns to normal position the diaphragm 113 rises thus causing the change of the insecticide in the casing 112 to be discharged through the pipe 104 and a spray nozzle 105 into a box therebelow. 40

As shown in Fig. 6 below the second reach of the conveyor chain 23 I provide a horizontal conduit 127 one end of which opens into the central column 17 and the opposite end into a vertical conduit 128 on the outside of the housing 45 12. The conduit 127 includes a pair of discharge nozzle members 129 spaced one at each side of the conveyor chain 23 and arranged to direct air onto the bottom of a box directly above the conveyor chain. 50

To allow air from the nozzles 129 to strike the box above the conveyor chain I provide idler rollers 130 and 131. The roller 130 is shown as rotatably mounted on a rod 132 supported in bosses 133 one of which is on the central column 55 17 and the other on the chain guide 34. The other roller 131 is pivotally mounted on a boss 134 on the pipe 49.

The rollers 130 and 131 are of sufficient diameter so that when a box engages them and 60 passes thereover it is raised off the conveyor chain 23 thereby allowing fluid from the nozzles 129 to strike the bottom of the box formerly engaged by the conveyor chain.

Above the conduit 127 I provide a similar horizontal conduit 135 one end of which opens into the vertical conduit 128 and the opposite end is closed. The conduit 135 includes an elongated downwardly directed discharge nozzle portion 136 to direct air downwardly into a box. 65 70

As shown in Fig. 13 at another station on the apparatus I provide a horizontal conduit 137 one end of which opens into the central column 17 and the opposite end into a vertical conduit 138 on the exterior of the housing 12. The con- 75

duit 137 includes a plurality of downwardly directed discharge nozzles 139 and 140. The nozzles 139 are angularly arranged to direct air onto the inner face of the inward side of a box and the nozzles 140 are angularly arranged to direct air onto the inner face of the outside of the box.

Below the second reach of the conveyor chain I provide a horizontal conduit 141, one end of which opens into the vertical conduit 138 and the opposite end is closed. The conduit 141 includes an elongated upwardly directed discharge nozzle portion 142 for directing air against the bottom of a box as it passes therover.

Above the third reach of the conveyor chain I provide a horizontal conduit 143 one end of which opens into a vertical conduit 144 on the outside of the housing 12. Opening into the conduit 144 the side wall 14 of the housing 12 has an elongated vertical slot 145 therein in which a discharge nozzle member 146 is positioned with the discharge end of the nozzle flush with the inner face of the side wall 14.

Opposite the discharge nozzle 146 the central column 17 has an elongated slot 147 therein in which a discharge nozzle member 148 is positioned with the discharge end of the nozzle flush with the outer face of the column 17.

The discharge nozzles 146 and 148 direct air onto the outer surfaces of the side walls of a box as it passes thereby.

Steam generated in the tank 65 and from the water in the bottom of the housing mixes with the air circulated by the blower 18 and forms a fog in the apparatus. To remove this fog from a box before it leaves the apparatus I provide a blower member 150 which includes an inlet 151 and an outlet 152. The blower 150 is shown as including a drive sprocket 153 which is driven by a sprocket chain 154 from a sprocket 155 on the armature shaft of a motor 156.

One end of an inlet conduit 157 communicates with the blower inlet 151 and the opposite end enters the housing 12 adjacent the exit B where it includes a downwardly directed portion 158.

One end of an outlet conduit 159 communicates with the blower outlet 152 and the opposite end enters the housing 12 adjacent the entrance A where it includes a downwardly directed portion 160.

From the foregoing it will be apparent that when the blower 150 is operating air will be drawn thereinto from the interior of the housing adjacent the exit B through the conduit 157 and be discharged through the conduit 159 into the housing adjacent the entrance A. Thus as a box passes below the portion 158 of the conduit 157 the fog in the box is withdrawn therefrom. As a box enters the apparatus and passes below the portion 160 of the conduit 159 fog is directed thereinto.

Boxes may be moved into the apparatus in any desired manner but in the accompanying drawings I have provided a short conveyor mechanism 161. The conveyor mechanism 161 includes an endless belt 162 mounted on a pair of spaced rollers 163 and 164. The roller 164 is supported on a shaft 165 which in turn is supported on a frame 166 suitably mounted on the housing 12. The roller 163 is mounted on a shaft 167 which is suitably journaled on the frame 166 and has a sprocket 168 thereon which is driven by a sprocket chain 169 from a sprocket 170 on the conveyor chain drive shaft 25.

Boxes may be placed on the conveyor mecha-

nism 161 in any desired manner such as by another conveyor device not shown. Boxes are preferably placed on the conveyor mechanism 161 with the open tops facing upward so that they enter and pass through the treating apparatus 10 with their open tops upward.

From the foregoing description it will be apparent that the box conveyed through the apparatus 10 on the conveyor chain 23 is first filled with a fog from the conduit 159 and at one point 10 a liquid insecticide is sprayed into the box by the nozzle 105. At another point hot foggy air is directed into the box by the nozzle 136 and at the same time the box is raised off the conveyor chain 23 and hot foggy air is directed from 15 the nozzles 129 against the bottom of the box formerly occupied by the conveyor chain. At still another point hot foggy air is directed against the inside surface of the side walls of the box by the nozzles 139 and 140 and at the 20 same time hot foggy air is directed against the bottom of the box by the nozzle 142. At still another point hot foggy air is directed against the outer surfaces of the box by the nozzles 146 and 148.

As a result of the repeated treatment at different locations the insecticide, fluid and hot foggy air is forced into all the cracks and crevices of the box and a thorough action is thus secured. This treatment insures that all portions of the 30 box will be reached.

It will thus be seen that with my apparatus 10 very little floor space is required for a long distance of travel of the box and that throughout the long period of travel the box is subjected to 35 heat and the action of hot fluid vapor or fog.

In Fig. 17 I have indicated a modification of my box treating apparatus generally at 172. The apparatus 172 is similar in most respects to the previously described apparatus 10 and like portions thereof are indicated by similarly primed reference numerals. The apparatus 172 is proportioned to receive and convey therethrough a box such as indicated at 173 which is positioned on the conveyor chain on one of its sides with 40 the open top facing outward. This necessitates placing the insecticide spray nozzle 105' on the side of the housing as shown in Fig. 18.

The side wall 14' of the housing 12' adjacent the inlet A' has an elongated slot 174 therein in 50 a position wherein it is approximately in line with the lower side of a box on the conveyor chain. The blower outlet pipe 159' opens through the side wall of the housing 12' above the slot 174 in a position so that it is slightly below the 55 upper side of a box on the conveyor chain.

The blower inlet pipe 157' opens through the side wall of the housing 12' at the outlet portion B' in a position intermediate the upper and lower side walls of a box on the conveyor chain.

When the apparatus 172 is operating and a box 173 moves into a position to receive the blast of air from the conduit 159' the air blast enters the box adjacent the top wall thereof, strikes the vertically disposed bottom of the box and moves downward striking the lower side wall of the box which directs it towards the slot 174 through which it passes carrying with it any leaves, dust or other refuse which may have been in the box 70 when it entered the apparatus.

From the foregoing description it will be apparent that I have provided a novel box treating apparatus which can be economically manufactured and which is highly efficient in use.

Having thus described my invention I claim:

1. In a box treating apparatus, a housing closed at the top and bottom, said housing including an entrance portion and an exit portion, one of said portions being adjacent the top of the housing and the other portion adjacent the bottom thereof, a central hollow column in said housing extending from the top to the bottom thereof, means to circulate fluid in said housing and said central column, a conveyor within said housing and outside of said central column, means to withdraw fluid from a box at said exit portion and to discharge it into a box at said entrance portion, and a conduit member extending outward from said central column and adapted to discharge fluid into the space between said column and the outer wall of said housing. 5
2. In a box treating apparatus, a housing closed at the top and bottom, said housing including an entrance portion and an exit portion, a conveyor between the entrance and exit portions, a central hollow column in said housing extending from the top to the bottom thereof, means to circulate fluid in one direction in said central column and in a reverse direction in said housing, a plurality of spaced discharge outlets extending outward from said central column and disposed to discharge fluid into the space between said column and the outer wall of said housing at various angles and means to withdraw fluid from a box at the exit portion and to discharge it into a box on the conveyor. 10
3. In a box treating apparatus, a housing closed at the top and bottom, said housing including an entrance portion and an exit portion, a central hollow column in said housing extending from the top to the bottom thereof, means to provide circulation through said housing and said hollow column, a plurality of spaced conduit members extending outward from said central column and adapted to discharge fluid into the space between said column and the outer wall of said housing, an endless conveyor positioned between said column and the outer wall of said housing and arranged in helical formation, a guide in said housing adjacent to the outer wall thereof and arranged in helical formation, an open topped container in the bottom of said housing between the outer wall thereof and said central column, the upper edges of said container being spaced above the bottom wall of said housing, a burner member in said container, means to supply fuel to said burner, a tank in said housing between the outer wall thereof and said central column, said tank being positioned above said burner, means to convey water into said tank, said means including a float controlled valve to maintain a predetermined water level in said tank, a blower member, said blower including an inlet and outlet, means to drive said blower, an inlet conduit having one end communicating with said blower inlet and the opposite end opening into said housing at said exit portion, an outlet conduit having one end communicating with said blower outlet and the opposite end opening into said housing at said entrance portion, a fluid supply tank associated with said housing, pump means, means connecting said pump means to said supply tank, a pipe leading from said pump means to said housing, the discharge end of said pump being disposed in said housing and directed to discharge into a box on said conveyor chain and means operated by a box on said conveyor chain for actuating said pump means. 15 20 25 30 35 40 45 50 55

CHARLES B. COOK. 55
